UNITED STATES PATENT OFFICE.

WILLIAM E. MILLIGAN, OF NEW YORK, N. Y.

RAILROAD-CAR SEAT.

Specification of Letters Patent No. 10,818, dated April 25, 1854.

To all whom it may concern:

Be it known that I, WILLIAM E. MILLIGAN, of the city, county, and State of New York, have invented a new and useful improvement in car or carriage seats which require to be reversed, as in a railroad-car seat, or in a carriage-seat, or in a conversational sofa, or in any article of a like description which either requires to be reversed or may be reversed with advantage; and I do hereby declare that the following is a full and exact description of the manner of constructing the same, reference being made to the accompanying drawing, 15 wherein—

Figure 1, A is a perspective view of a seat complete for use. Fig. 2, B is an end or side view. Fig. 3, C is a front view of the seat and back, showing a bar running from 20 end to end, which acts as an axle for rollers or sheaves (a) and which traverse in the slot (b) in the end or side. Fig. 4, D is an end view of the seat with the back, without the shaft and without the rollers. Fig. 5, 25 (E E) are foot bars which also act as braces to secure the end pieces steady, and which may be used with or without screw nuts. If without screw nuts the end of each may be keyed or riveted, the object being to 30 stiffen and hold the frame together. Fig. 6, (F) is a bar extending from end to end one end of which is shown at (F'). This bar aids first in stiffening the frame; second, as a rest for the seat and which may 35 be secured in a like way as the foot bars. Fig. 7 is a bar or axle, upon which the rollers or sheaves may be made to traverse, the shoulder being so arranged that the rollers or sheaves will traverse easily.

40 The end pieces may be made of any description of metal, and of any variety of pattern or of wood, iron being the cheapest will be the best. The frame of the seat may also be of any description of metal or of 45 wood. The bar which extends from end to end of the seat, and which acts as an axle for rollers or sheaves (Fig. 7) may be of metal, wrought iron of five-eighths of an inch being preferred, although the diameter or thickness may vary to correspond 50 with the strength required. The sheaves may be of any diameter required to fill the slot in the pattern, each being of sufficient strength not to be crushed by the weight of 55 two or more persons.

The ends or sides (B), as hereinafter mentioned, may be of any description of metal or of wood, and may be made either open, as shown in the drawing, or solid, excepting the open space or slot, in which 60 the rollers or sheaves traverse.

The foot bars (E E) may be of metal or of wood. Iron is preferable because the strongest as well as the cheapest. The bar (F) may also be made of metal or of wood. 65 Iron is preferable for the same reason that iron is preferable for the foot bars. It will be seen that the bar F is a rest for the seat, although the seat absolutely rests upon two sets of lugs, an end view being shown 70 at F', F', and which extend out from the inner side of each end, and which are to be cast with the end. Each lug may extend out and be as wide as the constructor may require, or it may be let into the frame 75 and secured by either a screw nut or be keyed or riveted. It will be obvious however, that the lug when cast with the end will be the cheapest and the best. The axle bar for the rollers or sheaves may be made 80 of any metal, iron being the cheapest, and may be of any diameter from five-eighths of an inch upward, in proportion to the strength required. The bar is not essential, as a lug may be let into the frame at the 85 angle, or if the frame be made of cast metal, a lug may be cast with the frame, economy being consulted. The rollers or sheaves may be made of metal or of wood. When made of wood, hard wood should be used, 90 and lignum vitæ is the best; but it will be evident that cast iron will be most economical. The frame of the seat may be in one piece of metal or in several pieces, and may be of wood or metal, and either covered 95 with upholstery or made in any ordinary way, and when covered may be either with hair cloth or split cane or twisted flag, or any description of covering to suit the constructor, the whole forming a cheap as well as convenient seat for a car or carriage. 100 In all cases the frame is stationary. When the seat is to be reversed, the rollers are drawn back in the slot and the back being let down forms the seat, and vice versa.

I do not claim the device of making reversible seats in which the back turns down to form the seat and vice versa, such having been used before, but—

What I claim as my invention is—

110

Supporting the angle of the seat and
back upon ways or in any equivalent man-
ner whereby it is transferred from one side
of the chair frame to the other in making
5 the reversal, substantially as herein de-
scribed.

Given under my hand this twenty-sixth

day of October, in the year of our Lord
one thousand eight hundred and fifty-three.

W. E. MILLIGAN.
